UNITED STATES PATENT OFFICE.

CLARENCE W. HAZELETT, OF LAKWOOD, AND FRANCIS A. HOLT, OF CLEVELAND, OHIO, ASSIGNORS TO NATIONAL CARBON COMPANY, INC., A CORPORATION OF NEW YORK.

APPARATUS FOR FITTING INSERTS IN SEPARATORS.

1,392,155.

Specification of Letters Patent. Patented Sept. 27, 1921.

Application filed October 29, 1918. Serial No. 280,091.

To all whom it may concern:

Be it known that we, CLARENCE W. HAZELETT and FRANCIS A. HOLT, citizens of the United States, and residents, respectively, of Lakewood, in the county of Cuyahoga and State of Ohio, and Cleveland, in the county of Cuyahoga and State of Ohio, have invented a certain new and useful Improvement in Apparatus for Fitting Inserts in Separators, of which the following is a full, clear, and exact description.

This invention relates to apparatus for manufacturing separators for secondary batteries having hard rubber or other hard acid resisting inserts fitted in a thin sheet of wood veneer or other pervious material, as described and claimed in the patent to I. C. and C. F. Williams, No. 1,265,284, dated May 7, 1918.

Particularly the invention consists of apparatus adapted to form the inserts and fit them in a wooden separator which has previously been planed, grooved, cut to the required shape and treated in well known ways to secure a separator which in that form is in wide commercial use.

The object of the invention is to provide apparatus adapted to securely fasten the insulating inserts in the wood separators.

Another object of the invention is to provide a simple mechanism adapted to automatically and rapidly perform a number of operations which will be fully set forth in the following description and illustrated in the drawings in which:

Figure 1 is a front view of the apparatus.

Fig. 2 is a side view from the left of Fig. 1.

Fig. 3 is a central cross section of the punch frame used in Figs. 1 and 2.

Fig. 4 is a fragmentary side view of the punch and die frames of Fig. 2 on an enlarged scale.

Fig. 5 is a pseudo-perspective view of a plate resting on the base block of Fig. 4.

Figs. 6 and 7 are pseudo-perspective views of end blocks placed and adapted to fit upon the front end of the plate of Fig. 5.

Fig. 8 is a pseudo-perspective view of an end block adapted to fit upon the rear end of the plate shown in Fig. 5.

Fig. 9 is an end view on a reduced scale of the plate of Fig. 5.

Fig. 10 is an inverted plan view of a second plate adapted to be fitted upon the plate

of Fig. 5 between the end blocks, the former being on the same scale as Fig. 9.

Fig. 11 is an end view of the plate shown in Fig. 10, in an upright position.

Fig. 12 is a plan view of a sliding die plate which is placed between the plates shown in Figs. 5 and 10.

Fig. 13 is an end view of the sliding die plate which fits within a casing formed by the plates of Figs. 5 and 10, the corresponding end views being shown in Figs. 9 and 11.

Fig. 14 is a plan view of a third plate adapted to be arranged between the end blocks just over the plate shown in Fig. 10.

Fig. 15 is a side view of the plate shown in Fig. 14.

Fig. 16 is a cross section on the line A—A of Fig. 14.

Fig. 17 is a plan view of the uppermost plate and adjacent guides shown in Fig. 4.

Fig. 18 is a cross section on the line B—B of Fig. 17.

Fig. 19 is a fragmentary view of the lower rollers and the ratchet and gear drive for the rollers on an enlarged scale, the mechanism being adapted to fit between the plates shown in Figs. 5 and 10.

Fig. 20 is a fragmentary end view with surrounding parts removed to illustrate the roller and ratchet feed.

Fig. 21 is a perspective view of one of the upper rollers.

Fig. 22 is a perspective view of one of the bearing blocks for the rollers.

Fig. 23 is a somewhat diagrammatic cross section of the feed rollers and plates, showing the essential relationship of the parts and with the punch frame in operative relation to the preceding elements.

Fig. 24 is a fragmentary cross section taken on the line D—D of Fig. 1, illustrating the separator feeding mechanism.

Fig. 25 is a fragmentary view showing the upper portion of an apparatus having a modified arrangement for controlling the punch.

Fig. 26 is a detail plan view of the punch frame of Fig. 25.

Fig. 27 is a cross section on the line C—C of Fig. 26.

Fig. 28 is an inverted plan view of a plate for use in the modification of Fig. 25 which combines the elements of Figs. 10 and 12 of the arrangement first illustrated.

Fig. 29 is an end view of Fig. 28.

Fig. 30 is a cross section of a separator having the inserts incompletely embedded therein.

Fig. 31 illustrates the manner in which 5 rollers press the inserts level with the surface of the separators if the inserts are above the surface as in Fig. 30.

In Figs. 1 and 2 of the drawings a punch press is shown of a common commercial type 10 and the elements and their operation will not be described in detail except as they particularly concern the apparatus applied thereto and its operation. It will be evident in the course of the description that other 15 types of punch presses could be used, or a special type of press could be designed for the particular service, without departing from the spirit of the invention, but the press shown herein has been found to embody 20 the essential requirements and is more economical than it would be to embody applicants' apparatus in a special press.

The primary parts of the punch consist of base standards 1, 1 which carry an upper 25 framework 2, 2 having a platform 3 arranged across the front connecting the sides 2, 2 of the upper framework. At the upper ends of the members 2, 2 bearings are arranged for a crank shaft 4 having a centrally 30 located eccentric crank pin 5. The crank is intermittently rotated by means of a belt driven fly wheel 6 adapted to be connected to the shaft by means of a suitable clutch 7 which is controlled by a pivoted foot lever 8 35 connected to the clutch by the control rods 9 and 10. When the foot lever is held down the crank shaft 4 will rotate with the fly wheel 6 until the foot is removed, and the fly wheel and crank shaft will be thrown out of 40 engagement when the crank pin 5 reaches its uppermost position, in a well known manner by means of suitable mechanism well known in presses, which, however, need not be described herein, as the method of control and 45 mechanism is not novel and no claim is made to these elements except as features more or less essential in the operation of applicants' combination.

A punch head 11 movable up and down 50 between guides 12 is connected to the crank pin by means of a link 13. To the lower end of the punch head a punch frame shown in detail in Fig. 3 is connected in any suitable manner. The punch frame consists of 55 an upper plate 14 having a hollow neck 15 for attaching to the punch head and a punch carrying plate 16 spaced from the upper plate by a thick layer 17 of elastic material, preferably soft rubber. The plates 14 and 60 16 and elastic rubber 17 are held together by means of the bolts 18, 18 passing therethrough. A bar 19 threaded into the lower plate 16 passes through the hollow neck which serves as a guide and in conjunction 65 with the bolts 18, 18 acts as means to main-

tain the plates parallel to each other when the rubber 17 is compressed in a manner which will be described more fully. Four punches 20 are secured in the four corners of the bottom plate in any appropriate manner, although the invention is not limited to this number. 70

In accordance with the present invention the rubber inserts are punched from strips of so-called hard rubber which is fed under the 75 punches. For each punch a strip of rubber is provided, those on the left being designated by 21 and on the right by 21'. The strips are sufficiently flexible to be coiled on separate rotatable reels 22 from which they 80 are unwound as the material is fed under the punches. Two reels are located on each side of the punch press and each pair is supported by a single arm 23 projecting from one of the upper frame members 2. 85

The strips on opposite sides are simultaneously fed toward each other in an intermittent manner by means of mechanism operated from the crank shaft as follows: A pinion 24 on the end of the crank shaft opposite the fly wheel meshes with a gear 25 on a stud 26 projecting from the frame. The gear 25 has a diameter twice as great as that of the pinion so that it makes one half the number of revolutions of the punch crank 95 pin. A cam consisting of a groove 27 in the face of a plate 28 fastened to the gear 25 operates an arm 29 pivoted at 30 by means of a roller 31 projecting from arm 29 into the groove 27. The cam may be divided essentially into four parts 27', 32, 32' and 32'', 27' being a circular portion having its center coincident with the center of the stub shaft 26 and covering at least 180°, so that when the roller is in this portion of the 100 groove 27 the arm 29 is not raised or lowered and the punch crank pin makes one complete revolution. The portion 32 approaches the center and raises the roller 31 and arm 29 during a period somewhat less than one-fourth of the period of revolution of the gear 25, and the roller then passes into a smaller circular portion 32' of short 105 radius before reaching a fourth portion 32'' similar to the section 32 and joining again with the large semicircular part, in which the roller and arm are lowered to the original position. A projecting end 33 of the arm is connected by a universal joint 34 to a depending link 35 having a second universal joint 36 between it and a ratchet operating lever 37 shown enlarged in Figs. 19 and 20. The ratchet lever is loosely fitted on a shaft 38 and has a dog 39 which is depressed by means of a spring 40 against a 115 ratchet 41 keyed to the shaft 38. As the link 35 is raised and lowered the dog 39 on the ratchet arm 37 engages the ratchet to intermittently rotate the shaft 38. A crank connection 42 is fastened to the oscillating 120

130

ratchet lever 37 by keying it to a projecting stud 43 and serves to operate a link 44 pivotally connected thereto for a purpose to be more fully described hereinafter.

- 5 On each side of the ratchet rollers 45, 46, formed on the shaft 38, are located in position to engage the strips 21 entering at the left of Fig. 1 and coöperate with two rollers 47 arranged immediately over the rollers 45, 46 to feed the strips 21 intermittently. Bearings for the aforesaid rollers are provided by blocks 48 and two similar lower blocks 49 of the form shown in Fig. 22. These blocks have the central portion cut 15 away to provide a space 50 for the rollers, and have semicircular notched ends 51, 51 adapted to fit the portions of the shaft 38 on each side of each of the lower rollers 45, 46, or the stubs 52, 52 of the upper rollers. 20 The lower blocks 49 rest on a supporting plate 53 which will be referred to hereafter, and the upper blocks 48 are fitted in grooves in a channel shaped frame 54, the location of which will also be set forth more fully 25 hereafter. To press the coöperating pairs of rollers together, a hole is arranged in each of the upper blocks 48 for receiving a spring 55 which is compressed to the desired degree by means of set screws 56 threaded 30 through the channel members 54.

A similar arrangement of rollers is provided at the right hand side of the apparatus for feeding the rubber strips 21' and consists of lower rollers 57, on a shaft 58 35 located in bearing blocks 59 coöperating with upper rollers 60 in bearing blocks 61 slidable in grooves of the channel 62. The corresponding pairs of rollers are similarly pressed together by set screws 63 and 40 springs 64.

The rotation of the two roller systems is coöordinated by means of a shaft 65 having similar spiral gears 66, 67 meshing respectively with gears 68, 69 on shafts 38 and 45 58 to provide mechanism adapted to simultaneously feed strips 21 and strips 21' intermittently toward each other at the same rate.

All of the feeding mechanism shown in Figs. 19 and 20 is combined with the die 50 mechanism in a manner which will be made clear in the following description of the die arrangement. The plate 53 shown in Fig. 5 rests upon the platform 3 and has an irregular channel 70 providing bearings 71 55 and space for the intermediate shaft 65, as well as depressions 72, 73 for the spiral gears 66 and 67. Upon the plate 53 a strip 74 is fitted at the rear end and provided with suitable interlocking grooves, as well as a semi-circular notch 75 coöperating with the rear notch 71 to form a bearing for one end of the shaft 65.

Two blocks 76, 77 are fitted at the front end upon the plate 53, leaving an intermediate space for the ratchet lever 37. Notch 65

78 serves as the upper part of the bearing for the front end of the shaft 65. Between the end blocks 74 and the blocks 76, 77 is placed the plate 79 (Fig. 10) which rests upon the plate 53 and the channel 80 provides space for one-half of the shaft 65. Portions are cut away at 81, 81' for spiral gears 66 and 67 respectively; at 82, 82' for gears 68 and 69; at 83 for shaft 58 and at 84 for the shaft 38 and its bearing blocks 45; at 84' for crank arm 42 and ratchet wheel 41; and at 84'' for ratchet lever 37. The plate 53 has a wide central groove 85 (Fig. 9) and plate 79 has a similar groove 86 (Fig. 11) which adjoins the groove 85 to provide a space adapted to form a guide for a sliding plate 87 (Figs. 12 and 13).

The sliding plate 87 is connected by means of the link 44 to the oscillating crank 42. Four dies 88 fitted in the sliding plate project above the upper surface of the plate into guide notches 89 of the plate 79. The holes in the dies are spaced apart exactly the same distance as the four punches 20 which coöperate therewith.

A plate 90 shaped similarly to plate 87 has cut away ends corresponding with those of the plate 79 for substantially the same purpose and is fitted in a similar manner between the end blocks 74, 76 and 77, the 95 combined thickness of the two plates being the same as the height of the blocks. A central slot 91 is cut in the lower surface of the previously mentioned plate and is adapted to serve as a guide for passing a separator therethrough, the top of plate 79 forming the bottom of the slit, the direction of said slit being from the front to the rear of the punch frame. In the center of the slit a spring 92 is fitted for the purpose of pressing the separator down against plate 79. A second set of dies 93 spaced the same as the punches 20 and dies 88, is fitted in plate 90. 100

The top member consists of the two channels 54 and 62 (Figs 19 and 20) previously mentioned, and a plate 94 (Fig. 18) therebetween having a slit 95 similar to that in Figs. 14 and 15 and similarly placed except that it is closed at the front end and has a pipe 96 tapped therein which leads down to 110 the base of the machine and is connected to a source of compressed air. The channels 54 and 62 and plate 94 have small slits 97 for admitting the rubber strips which are fed into the space 95 directly under four 115 holes 98 for admitting the punches. In the diagrammatic view (Fig. 23) the separator, dies and rubber strips are shown in operative relation, the manner of fastening the plate structure also being illustrated. Broadly 120 speaking, all of the plates are bolted together and to the base plate 3, except the sliding die plate, and the method of bolting need not be fully described.

In Figs. 1, 2 and 24 the apparatus for 130

- feeding the separators into the slit 91 is shown. This consists of a bracket 99 bolted to the front of the press having a hopper or receptacle 100 thereon for the separators.
- 5 The bracket has a grooved side 101 for a slide 102 which is adapted to reciprocate under the base of the pile to remove one separator at a time. Between the hopper 100 and the front of the slit 91 a roller 103 is mounted on lugs 104 and has a handle 105 projecting out at one side for operating the roller which is spaced above the bottom 106 of the bracket a distance slightly less than the thickness of the separators. The rotation of the crank handle also serves to operate the slide by means of a mutilated gear 107 which meshes with a spur gear 108 having the same number of teeth as the mutilated gear so that one revolution of the 10 crank produces one revolution of the spur gear 108. This is transmitted to the slide by means of a crank 109 and a link 110 connected to a lug 111 of the slide which projects through a suitable slot in the bottom 15 of the bracket. In this manner one turn of the crank handle produces one complete back and forward movement of the slide to feed a separator to the roller 103.
- At the rear of the slit 91 a pair of rollers 30 113, 113 are pressed together by a spring 114, the shaft of the upper roller 112 being movable in a slot 115 to permit the distance between the rollers to be varied. The rollers are driven from the fly wheel shaft by 35 means of pulleys 116, 117 and belt 118 which drive the shaft of the lower roll 113, and the movement is transmitted to the upper by cog wheels 119, 120. A receptacle 121 receives the separators as they come 40 through the rolls.
- In the modification of Figs. 25 to 29, the 45 sliding die plate is eliminated by means of the following changes, although the remainder of the apparatus remains unchanged.
- Instead of the resilient insert, a sliding wedge 122 is fitted between upper and lower plates 123 and 124 which are connected together by means of bolts 125 and pins 126 (Fig. 25) threaded into the lower plate and 50 passing through the upper plate, having compression springs 127 located above the upper plate and held by the nuts 128. The sliding wedge has a tongue and groove guide with the lower plate, the tongue 129 being 55 on the lower plate and coöoperating with the groove of the wedge which fits between the dowel pins. As the upper punch plate 123 is raised and lowered the wedge is pulled in or out at certain strokes, as will be later set 60 forth, by means of an arm 130 pivoted at 131 to the frame 2. The arm is provided with a slot 132 coöoperating with a pin 133 extending from a lug 134 of the wedge. The arm 130, together with the pin 131 and 65 wedge 122, are moved in or out by means of

70 fingers 135, 136, attached to the link 35. The fingers are adapted to engage an extension 137 of the arm 130 at suitable times to control the position of the wedge. In view of the elimination of the sliding die, the plate 79 and the die plate 87 may be combined as shown in Figs. 28 and 29, the resulting plate 138 having stationary dies 139. The link 44 and crank 42 also are evidently unnecessary 75 in this modification.

At the commencement of the operation of the apparatus the hopper 100 will be filled with separators and to feed the first separator under the punches it will be necessary to turn the crank handle 105 through two 80 complete revolutions to feed two separators, and then through enough of the third revolution to place the feeding parts in the relative positions shown in Fig. 24, the handle being stopped when it is approximately vertical. The hopper and slide do not feed the separators directly under the punching mechanism, but push each separator far enough to permit the roller 103 to engage it. The roller then pushes the separator with 90 which it is in contact through the groove 101 and forces the preceding separator under the punches. The distance between the roller and punching apparatus is selected so that when the separator is fed as far as possible 95 by the roller, the preceding separator is properly placed for the punching operation. The slide is timed so that the next separator is not fed to the roller until some time after the roller has disengaged the separator, which permits the operator to turn the crank a certain distance beyond the vertical position without disturbing the separator which is under the punches.

In the present case the operator will begin 105 and complete the revolution of the crank in a vertical position, although any position could be selected which would easily permit the operator to judge when a revolution has been completed. At this time the gears 107 110 and 108 should be out of mesh, the mutilated portion of gear 107 being adjacent the gear 108. The crank 109 and link 110 are in the position shown which places the slide 101 and separator 150 in a position where the 115 separator is almost ready to be engaged by the roller 103. The frictional engagement of the roller 103 has moved the separator 151 forward as far as possible, and this pushes the preceding separator 152 into the 120 slot 91 of the plate 90 in position for punching. Although friction is generally sufficient to prevent the separators from sliding too far in the slot, a spring 92 is provided to press the separator against the top of 125 plate 79 to prevent it from moving too far.

After a separator is fed into this position the punch is placed in operation by depressing the foot pedal, causing the punches 20 to descend passing through suitable holes 98 130

in plate 94, through dies 93, and punching four holes in the separator by coöperation with the dies 88 in the sliding plate 87. The wood separators will be punched so readily 5 that the resilient rubber plate 17 in the punch frame will scarcely be compressed when the punches strike the separator.

The sliding die plate is brought to the correct position to coöperate with the punches, 10 as just set forth, by means of the cam 27 and link mechanism consisting of the arm 29, link 35, lever 37, crank 42 and link 44, which coöperate with the cam 27 to control the position of the sliding die plate. This position 15 of the die plate is secured when the roller 31 is in the large semicircular part 27' of the cam which maintains the die plate 87 stationary during the entire up and down stroke of the punch head required to punch holes in the wood separator. During the 20 next reciprocation of the punch head the rubber strips 21 are fed forward quickly while the punch is going down by means of the portion 32 of the cam 27 in conjunction with the arm 29, link 35 and ratchet lever 37 which turns the ratchet wheel 41 through an angle sufficient to turn the rollers 45 and 46 far enough to feed the rubber strips 21 forward the required distance. The manner 25 in which the upper spring-pressed rollers 47 coöperate with the lower rollers 45 and 46 to feed the strips will be apparent. By means of the spiral gearing 66, 68, 67 and 69, and shaft 65, the same feeding movement 30 is transmitted to the rollers 57 and 60 to feed the strips 21' in from the opposite side toward the strips 21. After the strips are fed forward the ratchet arm is held stationary when roller 31 rides into the small circular part 32' of the cam.

While the rubber strips are fed forward the coöperation of the cam surface 32 and the link work previously described, will move the sliding die plate 87 backward by 45 raising the ratchet lever 37 so that the openings in dies 88 are no longer in alinement with the punches 20. Meanwhile the punches 20 descend and punch four small circular inserts from the rubber strips 20 and 21' which are fed in over the dies 93 through the slots 97 in the guide members 54 and 62 into the space 95. The waste material from the strips is removed by means of the air blast applied to the space 95. This 50 prevents any of the waste material from the strips accumulating therein and becoming pushed in over the die. The inserts are carried down through the dies 93 by the punches into the wooden separators, but 55 cannot be carried through because the openings in dies 88 have been moved out of alinement with the punches so that the punches press the inserts against the solid faces of the dies thereunder, and firmly insert the 60 hard rubber disks. On the first reciproca-

tion of the punches to form the holes in the separator, it is necessary to pass the punches 20 through the separators and slightly below the face of the dies 88, to punch holes in the wood, but on the second reciprocation 70 the punches are forcibly stopped by the face of the dies 88 when they reach the top surface of the separator. The difference in the length of the two strokes is taken up by the resilient rubber insert 17 in the punch head. While the punches 20 are raised the ratchet lever 37 is again lowered by means of the section 32" of the cam, and the sliding die plate 87 is again moved forward so that the openings are in alinement with 80 the punches. The inserts are thus fitted in place by two revolutions of the fly wheel 6 and the crank shaft 4 operated thereby, which produces one revolution of the gear 25 and cam 27 connected thereto. The operator then raises the foot lever 8 to operate 85 the clutch 7 and throw the crank shaft 4 out of engagement with the fly wheel 6.

The next separator is then fed from the bottom of the hopper by turning the handle 90 105 which brings the slide 102 and separator 150 forward, and the roller 103 engages the edge of the separator which will then be carried forward by the rotation of the roller and will push the separator 151 into the slot 95 91 and at the same time force out the separator 152 which has just had inserts applied thereto. The gear 107 is mutilated and adapted to rotate the gear 108 through a complete revolution while in mesh therewith, 100 to permit the slide to merely feed the separator to the roller which will then feed the separator forward by frictional engagement therewith. During the idle period in which the roller is out of contact with separators 105 150 and 151, the movement of handle 105 will be stopped, and at this time the foot pedal may be depressed. Automatic means has already been tried for feeding these separators, but on account of the imperfections of the 110 separators it is preferable to feed these manually as the apparatus becomes clogged and might be damaged by feeding imperfect separators.

As the separator 152 having the inserts 115 therein is forced out of the slot 91 by the succeeding separators, it will be engaged by the positively rotated rollers 112 and 113 which serve to roll the inserts smoothly into the wood.

In the modification shown in Figs. 25 to 29, the sliding die plate, and consequently the link mechanism for operating it, are eliminated. The elimination of the sliding die is advantageous because the die opening 125 must be kept in exact alinement with the punches and the wear of the links, cam and connecting pins makes this difficult to maintain.

The operation of the modified mechanism 130

- is essentially the same as the former arrangement except that the sliding wedge 122 is moved in and out between the punch members 123 and 124 by means of the pivoted arm 130 which is moved in or out by the fingers 135 and 136 in engagement with the projection 137. The up and down movements of the punch head and extension 134 of the wedge are taken care of by means of the slot 132 for the pin 133. The wedge will be drawn out of the desired point to shorten the effective length of the punch head or stroke on the reciprocation of the punch, which punches the inserts and fits them in the wood. The shortening of the effective length occurs during the time in which the roller 31 rides in the portion 32 of the cam where the link 35 is raised. The springs 127 serve to keep the wedge 122 and punch parts 123 and 124 in contact at all times. When the holes are punched in the wood the roller rides in the semicircular part of the cam and the wedge is pushed in to lengthen the punch head.
- 25 This method of shortening the punch stroke does not provide the resilient force for pressing the disks into the wood against the hard metal face of the die plate, but instead simply pushes them down into the holes in the separator the required distance, the die openings 139 below making it necessary to stop the punches before the disks are pushed too far through the wood. The relative positions of the inserts 141 and separator are often about as shown in Fig. 28, so that in this case the rollers 112, 113 are more essential than in the first modification, as they press the inserts down flush with the surface as shown in Fig. 29.
- 40 Having described our invention, what we claim is:—
1. In apparatus of the kind described, the combination of a die, strip feeding mechanism adapted to deliver a strip thereto, a support for a blank to be operated upon, a reciprocating punch and means coöperating therewith adapted to relatively adjust the support and punch on alternate cutting strokes for the purpose set forth.
  - 45 2. In apparatus of the kind described, the combination of a die, intermittently operating strip feeding mechanism adapted to deliver a strip to the die, a support for a blank to be acted upon, a second die coöperating with said blank, a reciprocating punch coöperating with both dies and means for adjusting the alternate cutting strokes of the punch to permit it to coöperate with the second die on alternate cutting strokes.
  - 55 3. In apparatus of the kind described, the combination of a die, intermittently operated strip feeding mechanism adapted to deliver a strip thereto, a support for a blank to be operated upon, a reciprocating punch adapted to coöperate with said die, and a re-

ciprocating die coöperating with the punch and blank on alternate cutting strokes of the punch.

4. In apparatus of the kind described, the combination of a stationary die, intermittently operated strip feeding mechanism adapted to deliver a strip over said die, a horizontal support for a blank to be acted upon, a vertically reciprocating punch adapted to coöperate with said die, and a reciprocating die coöperating with the punch and blank on alternate cutting strokes of the punch.

5. In apparatus of the kind described, the combination of a die, strip feeding mechanism adapted to deliver a strip thereto, a support for a blank to be operated upon, a reciprocating punch adapted to operate upon the strip and blank, and means coöperating with the punch and support for the blank, adapted to space the punch from the blank on alternate cutting strokes.

6. In apparatus of the kind described, the combination of a die, strip feeding mechanism adapted to deliver a strip thereto, a support for a blank to be operated upon, a reciprocating punch adapted to operate upon the blank and strip, and means coöperating with the punch adapted to shorten the length of alternate cutting strokes.

7. In apparatus of the kind described, the combination of a die, intermittently operated strip feeding mechanism adapted to deliver a strip thereto, a support for a blank to be acted upon, a reciprocating die adjacent said blank, a reciprocating punch adapted to coöperate with the dies, and means coöperating with the punch adapted to shorten alternate strokes thereof.

8. In apparatus of the kind described, the combination of a die, intermittently operated strip feeding mechanism adapted to deliver a strip thereto, a reciprocating punch, means coöperating with the punch to shorten the alternate strokes thereof, a reciprocating support and a die therein adapted to be placed out of alignment with the punch on alternate cutting strokes.

9. In apparatus of the kind described, the combination of a die, strip feeding mechanism adapted to feed a strip thereto, a reciprocating punch, a resilient insert in said punch, an abutment, and means for inserting the abutment in the path of the punch on alternate cutting strokes.

10. In apparatus of the kind described, the combination of a die, strip feeding mechanism adapted to feed a strip thereto, a resilient insert in said punch, a second die, a slideable holder for the second die, and a support for a blank to be acted upon adapted to be moved in the path of the punch to align the die and punch and compress the insert on alternate cutting strokes.

11. In apparatus of the kind described,

- the combination of a die, strip feeding mechanism adapted to feed a strip over the die opening, a vertically reciprocating punch, a resilient insert in said punch, a horizontally 5 slidable holder for a second die adapted to be moved into the path of the punch to align the die and punch and compress the resilient insert on alternate cutting strokes and a holder for a blank to be operated upon 10 located between the first and second mentioned dies.
12. In apparatus of the kind described, the combination of a stationary die, strip feeding mechanism adapted to feed a strip 15 over the die opening, a vertically reciprocating punch, a support for a blank to be acted upon, means coöperating with the support and punch capable of relatively adjusting the same on alternate working 20 strokes, a second die, means for moving said second die to place it in alignment with the punch on alternate cutting strokes, and means for operating the strip feeding mechanism intermittently to feed a strip over the 25 first mentioned die on alternate cutting strokes.
13. In apparatus of the kind described, a framework having a supporting bed, a die plate slidable thereon, a reciprocating punch 30 adapted to coöperate with a die in said plate to form an opening in the blank which is to be operated upon on the first cutting stroke of the punch, a second stationary die plate having its die openings in alignment with 35 the punch, means for feeding a strip of material over said stationary die opening after forming the opening in the blank, means for moving said slidable die plate to close the opening in the blank after the first cutting stroke, and a punch head having a resilient insert therein adapted to coöperate with the slidable die plate to shorten the 40 second cutting stroke.
14. In apparatus of the kind described, a framework having a supporting bed, a die plate slidable thereon, a reciprocating punch 45 coöperating with the die plate, means for moving the die openings into alignment with the punch on alternate cutting strokes, a stationary die plate, said die plates being 50 spaced apart and adapted to receive therebetween a blank to be operated upon, strip feeding mechanism adapted to feed a strip over the second mentioned die openings, and means for intermittently operating said 55 strip feeding mechanism to feed a strip over the second mentioned die opening on alternate cutting strokes of the punch.
15. In apparatus of the kind described, a punch head, a block for holding the punch, a layer of elastic material between the block and punch head, and means passing through the head, layer and block and retaining said parts in slidable relation.
16. In apparatus of the kind described, a framework having a supporting bed, a die plate slidable on the bed, a reciprocating punch adapted to coöperate with the die plate on the first cutting stroke of the punch, a stationary die plate adapted to coöperate 70 with the punch, said die plates being spaced apart and adapted to receive a blank to be operated upon therebetween, means for intermittently feeding a strip of material over the stationary die opening, means for reciprocating the said slidable plate whereby the die openings therein are alternately placed in and out of alignment with the punch, and a punch head having a resilient insert therein adapted to coöperate with the 75 sliding die plate to alternately change the length of the stroke.
17. In apparatus of the kind described, a framework having a supporting bed, a die plate slidable thereon, means for feeding 80 blanks to be operated upon over said die plate, a reciprocating punch adapted to coöperate with the die plate on the first cutting stroke of the punch to form an opening in the blank, a stationary die plate above the 85 movable die plate and spaced therefrom to form a guide for the blanks, means for intermittently feeding a strip of material over the stationary die opening, and a punch head having a resilient insert therein adapted to coöperate with the sliding die plate to 90 alternately change the length of the stroke.
18. In apparatus of the kind described, the combination of a framework having a supporting bed, a reciprocating punch, 100 means for operating said punch, a two to one gearing connected to said operating means, a die plate slidable on the supporting bed and operated by the two to one gearing to cause the die opening to be placed in alignment 105 with the punch on alternate cutting strokes, means for feeding blanks over the die plate, a stationary die plate spaced from the movable die plate to form a guide for the blanks, means for intermittently feeding a strip of 110 material over the stationary die opening, and means coöperating with the reciprocating punch adapted to shorten the length of the alternate cutting strokes.
19. In apparatus of the kind described, a framework having a supporting bed, a plurality of reciprocating punches, means for simultaneously reciprocating said punches, a two to one gearing connected to said means, a die plate having a number of dies 115 therein corresponding with the punches, said plate being slidable on the supporting bed and operated by the two to one gearing to place the die opening in alignment with the punch on alternate cutting strokes, means 120 for feeding blanks intermittently over the die plate, a stationary die plate spaced from the movable die plate to form a guideway for the blanks, means for intermittently feeding a strip of material over each of the 125 130

die openings of the stationary die plate, said feeding means being actuated when the movable dies are out of alinement with the punch, a reciprocating punch head and means adapted to shorten the length of alternate cutting strokes.

20. In apparatus of the kind described, the combination of a framework having a supporting bed, a plurality of reciprocating punches, means for simultaneously reciprocating said punches, a two to one gearing connected to said means, a die plate having a number of dies therein corresponding with the punches, said plate being slidable on the supporting bed and operated by the two to one gearing to place the die openings in alinement with the punch on alternate cutting strokes, a stationary die plate spaced from the movable die plate to form a guideway for blanks to be operated upon, means for intermittently feeding a strip of material over each of the openings of the stationary plate, said strips being fed in on opposite sides of the supporting bed and simultaneously toward each other, a reciprocating punch head, and means coöperating therewith adapted to shorten the length of alternate cutting strokes.

21. In apparatus of the kind described, the combination of a supporting bed, a die plate slidable thereon, means for feeding blanks over said die plate, means for holding the blanks against the die plate, a reciprocating punch, a stationary die plate above the movable die plate and spaced therefrom to form a guide for the blanks, and means for intermittently feeding a strip of material over the stationary die opening.

22. In apparatus of the kind described, the combination of a reciprocating punch, a guideway for plates to be acted upon, a die below said guideway coöperating with the punch and plates adapted to form an opening therein, an intermittently reciprocating slide adapted to feed blanks from the guideway, said slide being operated to feed a blank to the guideway on alternate cutting strokes of the punch, strip feeding mechanism, and a second die coöperating with the

strip and punch, said dies and guideway comprising a passage for an insert punched from said strip adapted to permit the insert to be conveyed to said opening in the plate by the punch.

23. In apparatus of the kind described, the combination of a reciprocating punch, a guideway for plates to be acted upon, a die below said guideway coöperating with the punch and plates adapted to form an opening therein, an intermittently reciprocating slide adapted to feed blanks from the guideway, said slide being operated to feed a blank to the guideway on alternate cutting strokes of the punch, strip feeding mechanism, and a second die coöperating with the strip and punch, said dies and guideway comprising a passage for an insert punched from said strip adapted to permit the insert to be conveyed to said opening in the plate by the punch, and a pair of rollers coöperating with the guideway to receive blanks having inserts therein and adapted to press said inserts smoothly into the separators.

24. In apparatus of the kind described, a pair of die plates, means for feeding a separator between the die plates, means for feeding strips of material above the upper plate, a plurality of reciprocating punches, means adapted to alternately operate said punches to punch holes in the separator and strips, and means for shortening the stroke of the punch which acts upon the strips.

25. In apparatus of the kind described, a pair of stationary die plates, means for feeding a blank between the die plates and for feeding strips of material above the die plates, a reciprocating punch, a plate for supporting the punch, a punch head, a wedge between the punch head and punch plate, and means for moving the wedge between said punch head and punch plate to shorten the alternate cutting strokes of the punch.

In testimony whereof, we hereunto affix our signatures.

C. W. HAZELETT.
F. A. HOLT.
